(57) **CLAIM**

I claim the ornamental design for the extraction pitcher, as shown and described.

DESCRIPTION

FIG. 1 is a perspective view of the extraction pitcher showing my new design;

FIG. 2 is a front view of the extraction pitcher;

FIG. 3 is a top view of the extraction pitcher;

FIG. 4 is a left-side view of the extraction pitcher;

FIG. 5 is a right-side view of the extraction pitcher;

FIG. 6 is a bottom view of the extraction pitcher; and,

FIG. 7 is a rear view of the extraction pitcher.
